UNITED STATES PATENT OFFICE.

CHARLES ELIASON, OF LAWRENCE, NEW YORK.

SAW.

1,203,510.

Specification of Letters Patent.

Patented Oct. 31, 1916.

Application filed February 19, 1914. Serial No. 819,651.

To all whom it may concern:

Be it known that I, CHARLES ELIASON, a citizen of the United States, residing at Lawrence, county of Nassau, State of New York, have invented certain new and useful Improvements in Saws, the following being a full, clear, and exact disclosure of the one form of my invention which I at present deem preferable.

10 For a detailed description of the present form of my invention, reference may be had to the following specification and to the accompanying drawings, which illustrate my invention, wherein—

15 Figure 1 is a side elevation of my device; Fig. 2 is a vertical central section thereof; Fig. 3 is a horizontal section through the guides; Fig. 4 is a rear view of the device and Fig. 5 is a plan view of the end of the 20 guides.

25 My invention relates to a saw particularly devised for cutting out sections of flooring or other surfaces which have no exposed edge on which to begin a cut.

20 Referring to the drawings, B, B represent two parallel guide-bars mounted on a retaining base D, which stands at right angles to the bars, and embracing between them a sliding block A which is normally held in the position shown in Figs. 1 and 2 by means of a compression spring C which is interposed between the block and an abutment on the guide B. In block A is mounted the shaft of a semi-circular saw S, the shaft also being provided with an operating handle which is offset from the guide B as appears in Fig. 1. Normally the saw S is maintained by the spring C in the position shown in Figs. 1 and 2 with the saw projecting 35 below the lower surface of the base D. The saw is journaled on the block A by means of a block A¹ against the rear side of which the saw S is seated and retained in place by screws s. A pin P is passed through the 40 block A¹ and has an enlarged portion upon which the said block and the saw secured thereto are free to rotate. A separating washer b is placed between the block A and the block A¹ to prevent binding of the saw.

45 The smaller portion of the pin P passes through the block A and is secured therein by a nut. A rod K extends upward from the block A through the spring c and also passes through the cross-bar which joins the 50 two guides B, B at the top, while the said

cross piece is turned over at its rear edge to form a grip or handle V.

The handle H is detachably secured to the block A¹ by means of the screw h and a thumb-nut thereon. The lower end of the 60 handle H enters an undercut slot in the outer surface of the block A¹ and the screw h is then passed through the block A¹ and the thumb-nut applied.

A hook-latch T projects downward from 65 the cross piece on the rear side of the apparatus and engages a lug t on block A whenever the block is lifted against the force of the spring and is thereby retained in its upper or non-cutting position. By holding 70 the apparatus down, either with the hand or grip V or with the foot or base D, and pulling up on the handle H the block A can be readily drawn upward in the guides against the force of the spring until it is caught by 75 the latch T.

On the under side of the base D are two pointed lugs d which may be used if desired to prevent the sliding of the base D on the 80 floor.

In operation the base D is placed against the floor W or other surface in which the cut is to be made, while the block A is drawn up and latched. The periphery of the saw will be on a line with the lower surface of the base D and in contact with the floor along the line to be cut, the plane of the saw being made to conform to the direction of the cut. Then the base D will be securely held by the foot, or other pressure, 85 such as might be exerted through the grip V, and the latch T moved back by the finger to release the block A and allow spring C to force the saw against the floor W. Then the saw will be oscillated by the handle H and, 90 being held against the work by the force of the spring, it will cut into the floor and by means of the spring the saw will follow down into the cut as the cut deepens.

95 What I claim as-new and desire to secure 100 by Letters Patent is:

1. A surface-cutting hand saw comprising a base having a flat under surface adapted to be supported upon and pressed against any part of the surface to be cut, a guideway 105 projecting upwardly from said base and of a strength to resist the side thrust thereon, a carrier traveling in said guideway, a saw-block journaled on said carrier, a flat saw attached to said saw block, said saw having 110

its edge convexly curved in the plane of the blade, the thickness of the saw being supplemented by said block, a spring acting to press the saw beyond the underside of the base, a rearwardly extended grip attached to and closing the upper end of said guideway, and a handle attached to said saw block.

2. A device for sawing through floors or other flat surfaces, comprising a substantial frame, comprising a base placeable on a flat surface and upon which the operator may place his foot, spaced rigid uprights affording a guideway between them, a carrier slideable in said guideway and a block pivoted to said guideway and carrying and rein-

forcing a flat convex edged saw so that the latter may be projected beyond the work engaging face of said base and there oscillated, and a handled lever on the block extending 20 above the guideway and offset laterally therefrom so that it may be conveniently grasped and oscillated by an operator having his foot upon the base.

In witness whereof I have hereunto set 25 my hand, before two subscribing witnesses, this twenty-sixth day of January, 1914.

CHARLES ELIASON.
